UNITED STATES PATENT OFFICE.

CHARLES R. BELK, OF PITTSBURGH, PENNSYLVANIA.

AUTOMATIC BLOWER-VALVE.

1,359,317.

Specification of Letters Patent. Patented Nov. 16, 1920.

Application filed October 2, 1919. Serial No. 327,879.

To all whom it may concern:

Be it known that I, CHARLES R. BELK, citizen of the United States, residing at Pittsburgh, in the county of Allegheny and State of Pennsylvania, have invented certain new and useful Improvements in Automatic Blower-Valves; and I do hereby declare the following to be a full, clear, and exact description of the invention, such as will enable others skilled in the art to which it appertains to make and use the same.

This invention relates to blower valves for creating a draft in a locomotive from a steam chest or steam pipe, and inoperative when the engine is not working steam, standing or in motion.

An object of this invention is to provide a valve of this type which does not have an outlet to the atmosphere, and thus cause a beclouding of the vision of the enginemen, and in conjunction therewith accomplish the purposes and functions desired.

A further object of this invention is to provide a device equipped with one connection whereby a locomotive can be fired up by the use of steam or air while out of service in the round house or any other suitable place where locomotives are fired up.

A further object of this invention is to reduce the number of operative parts of a device of this character and to consolidate the functions of several devices which have heretofore been used, such as, round house blower for firing up locomotives, automatic cut off valve for governing steam, right angle flange attachment to smoke box, safety valve at fire up connection in which steam or air can enter but not return, and provide an overbalance steam tight blower cap which will not shake off when it becomes loose.

A further object of this invention is to provide a device of this character that will function for the purposes desired and that will be connected to the smoke box of a boiler rather than to the steam chest.

With these and other objects in view, the invention consists of the construction, combination and in detail of arrangement of parts as hereinafter more fully described and claimed.

In the drawings:

Figure 1 is a side elevation partly in section of a locomotive with my attachment.

Fig. 2 is a section at 2--2 of Fig. 1.

Fig. 3 is a section medially through the valve.

Fig. 4 is a section at 4--4 of Fig. 3.

Fig. 5 is a section at 5--5 of Fig. 3.

Fig. 6 is an interior view of cap 25. 60

Fig. 7 in detail is a top view of nut 16.

Fig. 8 in detail is a bottom view of nut 16.

Fig. 9 is a top view of the principal valve.

In detail, a back head 2 of a locomotive 3, furnishes steam through a conduit 4 regulated by a valve 5 to principal valve mechanism herein 6 and from thence through a conduit 7 to the smoke box of a locomotive. When steam is in the steam chest it passes through a conduit 9 into valve 6 and closes 70 the egress of steam to conduit 7.

In detail valve 6 comprises a valve member 10, having a valve seat 11, the said member having horned projections 12 and recessed at 13 to receive a spring 14 and a guide member 15, said guide member 15 being integrally formed with a screw thread member 16 serving also the purpose of a reducer nut and steam inlet from said steam chest 8 and also screw thread to receive pipe 80 conduit 9; an auxiliary valve 17, having a seat 18 and a stem 19 is yieldingly held in place by a spring 20 and closes a conduit 21. The said conduit 21 is normally closed by a cap nut 22 and gasket 23 and is screw threaded at 24 for jointing with a conduit from a round house connection. Cap nut 22 is weighted at 25 so that the vibrations of the locomotive will keep it from becoming loosened. Conduit 4 is screw threaded 90 into the valve at 26 and the valve is affixed to the smoke box 27 and held in desired position by projections 28.

In operation, steam from the back head 2 passing through conduit 4 will normally pass through valve 6 and conduit 7 and create a draft through the smoke box. When, however, there is sufficient pressure of steam in the steam header 8, this steam passes through conduit 9 and lifts valve 10 against the pressure of the steam through conduit 4, and because of the greater surface to steam pressure through conduit 9, overcomes the pressure through conduit 4 and causes the valve 10 to be seated upon its seat 11, thus closing the passage from conduit 4 to conduit 7. Thus, when the locomotive is in operation and the steam header is under sufficient pressure of steam, no steam passes to the smoke box. 110

When in the round house or other terminal it is desired to provide the effect of a blower in the smoke box, all that is necessary is to remove the cap 22 and insert in threads 24 a conduit connection from the local steam container, the pressure of which will open valve 17 and form a continuous conduit through pipe 7. It is therefore obvious that in a simply constructed device 10 comprising a housing member, a pair of valves and a pair of screw threaded members, and a gasket and a pair of springs, the multiple functions of four devices are accomplished, namely, a round house blower 15 for firing up a locomotive, an automatic cut off valve for governing steam, a right angle flange attachment to smoke box and a check valve at fire up connection.

What I claim is:

- 20 1. In a blower for creating a draft in a locomotive, in combination, a conduit from a back head to a smoke box, a valve operative to close said conduit by the pressure of steam from a steam header, the housing for said valve placed upon the side of the smoke box of said locomotive, and said housing also constructed to receive a conduit for letting in steam at terminals.
- 25 2. In a blower for creating draft in a locomotive, in combination, a conduit from a back head to a smoke box, a valve operative to close said conduit, by the pressure of steam from a steam header, the housing for said valve placed upon the side of a smoke box of said locomotive, and said housing also constructed to receive a conduit for letting in steam at terminals, and an auxiliary valve in said housing for preventing accidents in case the cap for said terminal conduit is left off.
- 30 3. In a blower valve, in combination in a unitary structure, means for receiving a conduit from a back head, means for receiving a conduit from a steam header, means for receiving a conduit into a smoke box and means for receiving a conduit from an auxiliary supply.
- 35 4. In a blower valve for a locomotive, a three way T, adapted to receive from its lower portion, a conduit from a steam header and to close said valve by steam through said conduit under predetermined relative pressure to another conduit, triple lateral entrances to said T; one of said lateral en-

trances from a back head, another of said entrances for auxiliary supply, the said auxiliary supply entrance being closed with a valve, and another of said lateral entrances for connection with a conduit leading to a smoke box.

5 5. A four way T provided with a seat in one of its ways, and a cylinder in the way opposed to said seat, and another seat in the way at right angles to said opposed way, a valve and piston member in unitary structure 60 slidable in said cylinder and adapted to seat itself on the seat opposed to said cylinder, another valve mounted to seat itself on said other seat.

6. A blower valve comprising a unitary 70 housing provided with a transverse conduit and an L conduit at right angles to said transverse conduit, a valve member forming a piston in said L conduit and seating itself in juxtaposition to the elbow of said L, and 75 a secondary valve mounted in said transverse conduit.

7. In a blower valve in a locomotive, a member having a piston part on one end and on the other end a valve part for closing a conduit from a back head to a smoke 80 box said member being vertically mounted with the valve part yieldingly held upon its seat by a spring internal of said valve, said spring supported upon a perforated nut located below said piston and screwed into a vertical bore in alignment with said valve, said valve and piston being in one piece and said seat being located above said piston.

8. A blower valve comprising a unitary 90 housing provided with a transverse conduit and an L conduit at right angles to said transverse conduit, a valve member forming a piston in said L conduit and seating itself in juxtaposition to the elbow of said L, and 95 a secondary valve mounted in said transverse conduit, both said valves being normally held seated by means of springs.

9. A blower valve comprising in combination a valve admitting steam from an auxiliary source to smoke box, a steam pressure controlled valve admitting steam from back head to smoke box, and means for independently holding both of said valves normally seated, so that steam applied from 100 auxiliary to smoke box cannot enter boilers.

In testimony whereof I affix my signature.
CHARLES R. BELK.
